No. 617,154.

Patented Jan. 3, 1899.

O. GATES.

THEATRICAL STAGE APPLIANCE.

(Application filed July 18, 1898.)

(No Model.)

UNITED STATES PATENT OFFICE.

OLIVE GATES, OF NEW YORK, N. Y.

THEATRICAL STAGE APPLIANCE.

SPECIFICATION forming part of Letters Patent No. 617,154, dated January 3, 1899.

Application filed July 18, 1898. Serial No. 686,312. (No model.)

To all whom it may concern:

Be it known that I, OLIVE GATES, residing in New York city, Brooklyn borough, in the State of New York, have invented a new and useful Improvement in Theatrical Stage Appliances, of which the following is a full and exact specification.

My invention relates to that class of mechanisms which are made use of upon the stage to give the appearance of greater realism to representations of natural objects, and particularly to representations of flowing water.

I am aware that representations of rain and of falling water have been used upon the dramatic stage; but hitherto no device has been known by which a practicable rapid or flowing stream could be utilized to carry a canoe or other water craft or apparently-floating object. The appearance of the flowing water is very effective, and as the mechanical means are entirely concealed by a suitable adjustment of scenery the stage effect is highly realistic. This effect is entirely novel and is increased, and the device is utilized in dramatic representations by the use of the boat hereinafter referred to; but this combined effect and utility is only obtainable through the use of a device producing the natural effect of the flowing water.

Referring to the accompanying drawings, Figure 1 is a perspective view of a portion of a stage provided with my appliance. Fig. 2 is a cross-section on the line 2 2 of Fig. 3 of the mechanical part of my invention, and Fig. 3 is a longitudinal section on the line 3 3 of Fig. 2.

Similar letters represent like parts in the several figures.

A is the bed or base of the apparatus and is provided with sides F F to retain the water.

B is an opening or slot adapted to receive the guide d', which is attached to the boat C and extends below the base A and is provided with rollers d d, arranged upon it so as to retain it below the base and within the slot with as little friction as possible.

E is a metal or other lining secured upon the bed and preferably provided with transverse corrugations and having the smooth 50 countersunk channels e e on either side of the slot B.

The boat C is provided with supporting friction-rollers D D, adapted to bear the boat

along the channels e e, and with the guides d' d', which retain the boat upon the ways 55 and guide it in the line of the slot B.

T is a representation of a rock or other object arranged at the upper end of the device to conceal the entrance to the slot and chute.

In the practical operation of my device the 60 guides d' d' are introduced into the slot B at a portion of the chute which is concealed behind the rock T. The rollers D D support the boat C upon the ways or channels e e, and the force of gravity causes the boat to slide 65 to the other end of the apparatus, which is also arranged beyond the public view. W indicates the water. While passing along the chute, the guides d' d' retain the boat in the desired direction and in conjunction with the 70 rollers preserve its upright position. The water rippling over the corrugations of E will add to the naturalness of the scene.

In the practical working of my device it will often be found necessary to vary the 75 pitch and curves of the chute and to arrange different objects as screens at the ends and to make additions of other scenic features. For example, I have shown my invention in Fig. 1 in connection with a waterfall placed 80 at the head or upper end of the chute; but such a combination is not necessary to the practical use of my invention, the essential features of which are the inclined chute and the devices for guiding and retaining the boat 85 or other apparently-floating object in its desired position.

Having thus described my invention, what I claim as new, and desire to secure by Letters Patent of the United States, is—

In a mechanical stage appliance, the combination with a boat or similar object having guides affixed thereto and friction devices arranged upon the same, of an inclined chute or waterway adapted and intended to support such boat and to permit and control the passage of water over its own surface and provided with a slot or guideway adapted to receive and hold the guide or guides affixed to such boat, all substantially as and for the 100 purpose set forth.

OLIVE GATES.
